UNITED STATES PATENT OFFICE.

OVERTON WINSTON, OF MINNEAPOLIS, MINNESOTA.

HEADLIGHT.

1,346,520.

Specification of Letters Patent. Patented July 13, 1920.

Application filed December 2, 1915, Serial No. 64,661. Renewed December 12, 1919. Serial No. 344,464.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to electric headlights for automobiles and other vehicles, and is in the nature of an improvement 15 on, or modification of, mechanism disclosed and claimed in my co-pending application Serial Number 50,296, filed September 13th, 1915, and entitled "Head lights." Particularly, the invention is directed to improved means for shifting the light bulb or 20 light source in respect to the reflector, or conversely, certain of which adjustments are for properly setting the lamp filament in respect to the focal center of the reflector, and 25 certain other of which movements or adjustments are for the purposes of throwing the light bulb to and from the axis or focal center of the reflector, when different lighting conditions are required. For example, 30 in country travel, powerful light beams of long projection are desirable, while for city travel, if the light be not dimmed, it must be projected onto the road more closely in front of the machine, and there must be no 35 upwardly projected blinding rays. My invention provides simple and efficient means for accomplishing adjustments for the purpose above noted, and it further provides for various adjustments, such as axial lateral 40 and rotary adjustments of the light bulb in respect to the reflector. Such adjustments are required to effect proper initial setting of the lamp in respect to the reflector, and thereafter making changes which may be desirable to offset changed conditions, such as 45 warping of the lamp filament.

In the accompanying drawings which illustrate the invention, like characters indicate like parts throughout the several views.

50 Referring to the drawings:

Figure 1 is a vertical section taken through an automobile headlight designed in accordance with my invention;

Fig. 2 is a section taken approximately on 55 the irregular line $x^2 x^2$ of Fig. 1;

Fig. 3 is a fragmentary horizontal section taken on the line $x^3 x^3$ of Fig. 1;

Fig. 4 is a transverse section taken approximately on the line $x^4 x^4$ of Fig. 3;

Fig. 5 is a fragmentary section on the line 60 $x^5 x^5$ of Fig. 1;

Fig. 6 is a detail in section on the line $x^6 x^6$ of Fig. 1;

Fig. 7 is a detail showing the lamp socket structure in side elevation and a portion of 65 the reflector in vertical section;

Fig. 8, except in the reflector, shows the same parts that are shown in Fig. 7, partly 70 in side elevation, but chiefly in vertical section;

Fig. 9 is a rear elevation of the parts shown in Fig. 8, some portions being broken away;

Fig. 10 is an enlarged fragmentary view 75 partly in side elevation but with some parts sectioned on the line $x^{10} x^{10}$ of Fig. 9;

Fig. 11 is an enlarged section taken on the line $x^{11} x^{11}$ of Fig. 8;

Fig. 12 is a fragmentary section on the line $x^{12} x^{12}$ of Fig. 11 showing certain of 80 the parts shown in Fig. 11; and

Fig. 13 is a detail partly in elevation and partly in section illustrating a slightly modified arrangement of the lamp socket.

The numeral 1 indicates the casing of an 85 ordinary headlight, such as used on automobiles, and the numerals 2 and 3 indicate, respectively, the reflector and the lens or glass plate of the headlight. The electric light bulb 4 illustrated is of the well known Edi- 90 swan single base type, but, of course, other types of electric light bulb may be employed. As shown, however, the said bulb has an outer contact sleeve 5 and an axial contact boss 6. The sleeve 5 is adapted to 95 be telescoped into a lamp holding collar 7 that is swiveled in the end of a lamp socket made up of a pair of telescoping cylindrical shells 8 and 9. Preferably, the collar 7 is provided with an eccentric flange 10 that is 100 seated in the flanged front end of the shell 9 with the axis of the said collar, and hence, of the lamp bulb eccentric to the axis of the socket or lamp support made up of the said members 8 and 9. In the modified form, 105 however, shown in Fig. 13, the collar 7 has a concentric flange 10^a, which, while it adapts the said collar for rotation on its axis, always holds the light bulb with its axis concentric to the axis of the socket. 110

The sleeve 5 of the light bulb is provided with diametrically projecting pins 11 adapted to be inserted through grooves 12 formed in the interior of the collar 7, as best 5 shown in Figs. 11 and 12. The inner end surface of the collar 7 is serrated, corrugated, or otherwise roughened, and when the lamp is inserted into the socket, as shown in Fig. 8, its pins 11 will engage the said 10 roughened or serrated surface and hold the bulb against accidental rotation in respect to the said collar.

A nut 13 in the form of a cylindrical hub, is swiveled to the rear end of the outer 15 shell 8, but held against axial movements in respect thereto. This nut 13 engages the threaded stem 14 of a cylindrical contact holder 15 which is of well known construction and is rigidly secured by friction, or 20 other suitable means, in the inner shell 9, with its spring-pressed contact 16 engaged with the contact boss 6 of the light bulb.

The outer shell 8 of the light bulb socket or lamp support (see particularly Figs. 1, 25 3 and 4) is pivotally mounted at its front end on the conical points of the pivot screws 17. Thus, the lamp socket is mounted for vertical oscillatory movements, but is held against horizontal oscillations and against 30 rotation on its own axis. The inner shell 9 is provided with a projecting guide lug 18 that works in a longitudinal groove 20 of the outer shell 8 and thereby holds the said inner shell against rotation, but free for 35 telescopic axial movements in respect to the said outer casing 8.

The manner in which the swivel connection between the nut 13 and shell 8 is made is best illustrated in Fig. 10, by reference to 40 which it will be noted that the nut, at its extreme inner end, has an outstanding flange 13^a preferably serrated on one face for engagement with the flanged rear end of the outer shell 8; and furthermore, the said 45 nut has diametrically opposite pins 13^b that engage the outer surface of the flanged end of the said shell 8. The serrated or roughened surface of the flange 13^a gives additional friction between the nut and shell 8 and assists in preventing accidental 50 rotation of said nut, under vibrations produced in travel and otherwise. As is evident, axial movements of the inner shell 9, in respect to the outer shell 8 are produced 55 by rotation of the nut 13. It is desirable that this may be readily done without opening the lamp casing; and hence, I provide in the back of the casing 1, a socket adjusting tool in the form of an outwardly sprung- 60 pressed screw driver, the said term "screw driver" being used in a broad sense to include any tool for operating a screw or similar adjusting mechanism. The said screw driver 21 is mounted to slide end- 65 wise and to rotate in the bearing 22 secured

to the back of the casing 1, and, as shown, having a detachable cap 23. Normally, a spring 24 retracts the screw driver and holds the same in an inoperative position. When the screw driver is forced forward, it is 70 adapted to engage with radial grooves or notches 25 formed in the rear end of the adjusting nut 13, so that when the said screw is then rotated, the nut may be rotated and the inner shell 9, together with the light 75 bulb, moved axially of the reflector.

The reflector 2, in the vicinity of its axis, has an opening through which the lamp socket projects with sufficient clearance to allow for considerable vertical oscillations 80 of the said socket. Surrounding the axial opening and rigidly secured to the back of the reflector is a flaring annular flange 26 (see particularly Figs. 1 and 4). Set into this tapered flange 26 is a tapered annular 85 rim of a hollow bearing head 27 that is detachably but rigidly clamped to the said flange 26 by a divided clamping ring 28, the ends of which are clamped together by short nut-equipped bolts 29, best shown in Fig. 4. 90 Diametrically opposite the upper and lower solenoids 30 are secured to the top and bottom of the head 27, and guide rings 31, preferably of brass, are secured the top and bottom of the upper and lower solenoids 95 with their axial passages alined with the axial passages of the said solenoids and with vertical perforations formed in the top and bottom plates of the head 27. Mounted to reciprocate vertically through the alined 100 passages of the said head, solenoids and guide rings, is a so-called fulcrum bar or plunger 32 that serves as armature cores and is formed at its center with an annular fulcrum 33, the rounded inner edge of which 105 bears against the exterior of the outer shell 8 of the lamp socket. Light U-shaped springs 34 applied to the ring 33 engage the shell 8 on opposite sides of the said ring, and tend to hold the lamp socket in a position with its axis at a right angle to the plane of the said ring 33. The fulcrum bar or plunger 32 is made of iron, and hence, will be acted upon by the energized solenoids and thrown either upward or downward, according to which of the solenoids is energized. For example, the full lines in Fig. 1 show the position of the fulcrum bar lamp socket and light bulb, when the upper solenoid is energized, at which time the filament of the light bulb will be at the axis 115 of the reflector.

To the upper and lower ends of the shifting fulcrum bar 32 are brazed, or otherwise secured, brass extensions 32^a, the ends of 125 which are threaded and screwed into the sleeve-like latch heads 35. These latch heads 35 have projecting stems 36 that work through perforations 37 in the top and bottom walls of the casing 1 and are provided 130

outside of the said casing with knurled or corrugated heads 38, by means of which they may be readily turned. Spring fingers 39 shown as secured to hubs 40 on the casing 5 1, engage the corrugations of the heads 38 and hold the latch heads 35 against accidental rotation. It should be noted, however, that the above described engagement between the fingers 39 and corrugations of 10 the heads 38, does not interfere with vertical reciprocating movements of the fulcrum bar 32. The numeral 41 indicates caps shown as detachably applied to the ends of the hubs 40.

15 For engagement with annular grooves 42 in the latch heads 35, spring-pressed latch bolts 43 are mounted for radial movements in the guide rings 31. As shown, the grooves 42 are made approximately V-shaped and 20 the ends of the latch bolts 43 are beveled or conical, so that the force exerted by the solenoids 30 will be sufficient to overcome the engagement between the said members and move the fulcrum bar 32 from one position 25 to another. The said latches, however, prevent accidental movements of the fulcrum bar and serve as stops to limit the oscillatory movements of the lamp socket, and hence, of the lamp bulb. Of course, by adjustments of the latch sleeves 35, the extreme 30 movements of the fulcrum bar, and hence, of the lamp socket and light bulb may be varied, and this, it is important to note, may be accomplished from the exterior of the 35 lamp casing.

In Fig. 4, the flanged end of the bearing head 27, the supporting flange 26 and the clamping ring 28 are shown as provided with nested seats and alining lugs at 44, 40 which insure setting of the lamp socket with the axis of its pivot 17 horizontal, and hence, with the lamp socket and bulb mounted for true vertical movements when the fulcrum bar 32 is shifted.

45 When the new bulb is inserted into the socket, adjustments will be required to bring the hot portion of the filament to the focal center of the reflector. To do this, the eccentric 10 should be turned by application 50 of the fingers to the collar 7, until the axis of the said collar is moved to the highest point, to-wit, in a vertical line over the axis of the lamp socket. Then by adjustments of the lower latch head 35, the fulcrum bar 32 55 may be lowered or raised, carrying with it the rear portion of the lamp socket and thereby moving the hot portion of the light filament to the axis of the reflector. This being done, by the above described manipulation of the screw driver 21, the lamp socket and bulb may be adjusted axially so as to bring the hot portion of the filament to that point on the axis of the reflector known as the focal center of the reflector. This adjustment of the light bulb is that which

gives the greatest light projection or longest light beam, and is, of course, desirable for country road travel.

For city driving, and especially where ordinances require dimming of lights, the 70 light bulb is moved above the axis of the reflector; and this is accomplished in the present instance by energizing the lower solenoid 30, which draws down the fulcrum bar 32 and the rear portion of the lamp socket and 75 carries the bulb upward, for example, to the position indicated by dotted lines in Fig. 1. The exact position in which the light bulb will be set in this upward movement may be varied by adjustments of the upper 80 latch head 35. As is evident, the downward movement of the fulcrum bar 32 and resulting upward movements of the light bulb will be stopped when the groove 42 of the said upper latch head is engaged by the upper latch bolt 43. In practice, it has been found that the filaments of the electric light bulbs will warp from usage so that they require readjustment to maintain the above noted desired adjustments, and especially, 85 the adjustment of the filament to the focal center of the reflector. These filaments are liable to warp in a good many different ways. If warped so that they are bodily offset at one side of the axis of the reflector, 90 correction may be made by turning the eccentric 10 in the one direction or the other, so as to bring the filament back to a vertical line intersecting the focal center.

Under some conditions, it is also necessary 100 to rotate the bulb within the collar 7 in order to bring the filament back to proper adjustment. If the rotary adjustments of the eccentric in order to bring the filament laterally back to the vertical line of the focal 105 center, has the effect of raising or lowering the filament perceptibly, such vertical disalignment may be corrected by the proper adjustment of the lower latch head 35. Obviously, the above described various adjustments make it possible to correct all sorts 110 of inaccuracies in the initial position of a light bulb in respect to a reflector. To rotate the bulb on its axis, without moving the eccentric 10, the collar 7 should be held 115 by the fingers against rotation.

What I claim is:

1. In a headlight, the combination with a reflector and a lamp, one of said members being movable axially in respect to the 120 other, one of said members being movable transversely of the axis of said reflector, and the said lamp being rotatably adjustable on its axis, independently of said other adjustments and without changing its adjustment 125 longitudinally of its axis.

2. In a headlight, the combination with a reflector, of a lamp mounted for movements on the axis of said reflector, and for movements transversely of the axis of said 130

- reflector and for rotary movements on its axis, independently of said other adjustments and without changing its adjustment longitudinally of its axis.
5. 3. In a headlight, the combination with a reflector and a casing, of a lamp support having a lamp holder mounted to rotate on its own axis without shifting the same longitudinally of its axis, and means operative 10 from the exterior of said casing for imparting adjustments to the said lamp holders, both axially and transversely of the axis of said reflector.
- 15 4. In a headlight, the combination with a reflector, of a lamp support therein, mounted for independent longitudinal and vertical adjustments, said support having a concentric holding collar rotatively adjustable without changing its longitudinal 20 position in said support, and an electric light bulb mounted for rotary adjustments within said collar.
- 25 5. In a headlight, the combination with a reflector, of a lamp support therein, mounted for independent longitudinal and vertical adjustments, said support having a concentric holding collar rotatively adjustable without changing its longitudinal 30 position in said holder, and an electric light bulb mounted for rotary adjustments within said collar, and means locking said bulb to said collar in its various rotary adjustments.
- 35 6. In a headlight, the combination with a reflector, of a lamp supporting socket, a fulcrum for said socket fixed in respect to said reflector, the said socket being axially adjustable on said fulcrum, whereby an electric light bulb held by said socket may be 40 adjusted toward and from said fulcrum, said socket having a rotatively adjustable eccentric holding collar, and an electric light bulb rotatively adjustable in said collar.
- 45 7. The combination with a reflector, of a lamp socket comprising an outer shell, an inner shell adjustable axially within said outer shell, and an eccentric collar swiveled in the end of said inner shell and adjustable axially therewith.
- 50 8. The combination with a reflector, of a lamp socket comprising a non-rotary shell and a lamp holding collar rotatively mounted therein, and an electric light bulb rotatively adjustable within said collar, the said 55 collar and bulb being rotatively adjustable together, or either being rotatively adjustable independently of the other.
9. In a headlight, the combination with a reflector, of a lamp socket having an eccentric rotatively adjustable lamp holding collar, rotatable without changing its axial adjustment, and independent means for imparting axial adjustments to the said holding collar.
10. In a headlight, the combination with a casing and a reflector therefor, of a lamp socket in said casing extended axially of said reflector and provided with an axially adjustable bulb supporting element, and a yieldingly retracted adjusting device in the form of a screw driver detachably engageable with the rear end of the adjustable element of said socket, to adjust the same and the light bulb axially of the reflector.
11. In a headlight, the combination with a casing and a reflector therefor, of a lamp support within said casing extended axially of said reflector and provided with an axially adjustable lamp holder, an adjusting device working in the back of said casing and detachably engageable with said axial adjustment of said lamp holder, and means for oscillating said support in respect to the axis of said reflector.
12. In a headlight, the combination with a reflector and a lamp support, one of which members is capable of oscillatory movement, of a casing inclosing said members, a plunger movable to oscillate the said oscillatory member, latches for limiting the movements of said plunger and holding the same in extreme positions, and adjusting devices for said latches extending to and operative from the exterior of said casing.
13. In a headlight, the combination with a casing and a reflector therefor, of a lamp support in said casing extended axially of said reflector and having an oscillatory movement in respect thereto, a plunger-like armature movable within said casing for oscillating said support, electro-magnets for reciprocating said armature, and latches for limiting the movements of said armature and holding the same in extreme positions, said latches having adjusting devices extended to and operative from the exterior of said casing.
- In testimony whereof I affix my signature in presence of two witnesses.
